UNITED STATES PATENT OFFICE.

ALFRED H. HAAG, OF BALTIMORE, MARYLAND.

PHONOGRAPHIC-DISK-RECORD CABINET.

Application filed February 21, 1922, Serial No. 538,186. Renewed May 20, 1924.

To all whom it may concern:

Be it known that I, ALFRED H. HAAG, a citizen of the United States, residing at Baltimore city, State of Maryland, have ⁵ invented certain new and useful Improvements in Phonographic-Disk-Record Cabinets, of which the following is a specification.

This invention relates to cabinets designed ¹⁰ more particularly for storing or housing disk records of phonographs, and its object is to provide the cabinet with a novel and improved ejector mechanism for facilitating removal of the records, and also to provide ¹⁵ a cabinet having its various parts so constructed and arranged that they can be readily assembled.

With the objects stated in view, the invention consists in a novel combination and ²⁰ arrangement of parts to be hereinafter described and claimed, and in order that the same may be better understood, reference is had to the accompanying drawings, wherein:

²⁵ Figure 1 is a perspective view of the cabinet; Fig. 2 is an enlarged cross-section thereof; Fig. 3 is a vertical section of a fragment of the cabinet, on the line 3—3 of Fig. 2; Fig. 4 is a longitudinal section of ³⁰ the upper portion of the cabinet; Fig. 5 is a perspective view of a tiltable record-supporting and ejecting member; Fig. 6 is a perspective view showing a modification of said member; Fig. 7 is a cross-section of a stop member, and Fig. 8 is a cross-section of an index-plate carrying rail.

The cabinet may be made in any suitable size to hold a plurality of record disks, and it is provided with a number of compartments in each of which a record disk is ⁴⁰ adapted to be placed. As the thickness of record disks of different makes varies, the compartments will be given such a width that each will hold a thick record or two ⁴⁵ thin records. Ordinarily however, only one record will be placed in each compartment. The compartments will also be given a depth and height to accommodate all the varying sizes of record disks.

⁵⁰ The cabinet is composed of end walls 10, a top 11, a bottom 12 and a rear wall 13. The end walls may be of wood or other light and cheap material, and for the top, the

rear wall and the bottom of the cabinet a single sheet of paste-board or similar material is employed which is laid over and secured to the top, bottom and rear edges of the end walls 10. The entire structure is covered on the outside with a fabric sheet 14 such as imitation leather or the like. ⁵⁵ The cabinet is open in front, and the end walls 10 are here connected by top and bottom cross strips 15 and 16 over which the sheet 14 is also laid. Inside the cabinet, at the rear wall 13, the end walls 10 are connected by a pair of vertically spaced cross strips 17.

The compartments of the cabinet are formed by partitions 18 extending between the top and the bottom thereof, and terminating short of the back of the cabinet, as shown in Fig. 2, so as to leave a single compartment at the rear portion of the cabinet. In this rear compartment, near the bottom thereof, is a cross rail 19 which extends between the end walls 10, and serves as a back stop for the records in the various compartments, the rear portions of the records being adapted to seat against said rail as shown in Fig. 2. ⁷⁰

⁷⁵ The partitions 18 are held in spaced relation by top and bottom spacer strips 20 and 21, and the entire assembly or partitions and spacer strips is secured by top and bottom rods 22 and 23. These rods extend horizontally between the end walls and pass therethrough, their ends being headed on the outside of said walls, as shown in Fig. 4. The partitions and spacer strips are apertured and the rods pass therethrough, the assembly of partitions and strips being thus ⁸⁰ strung on the rods.

The construction hereinbefore described ⁸⁵ enables the cabinet to be easily and cheaply built, and the various parts can be readily assembled.

Near the bottom of the cabinet is a horizontal rod 24 which extends between and is secured to the end walls 10, and passes through the partitions 18. This rod is located above the bottom filler strips 21, and hence it crosses each compartment. Secured to and extending between the end walls 10, near the open front of the cabinet, are two horizontal cross rods 25. These rods also ¹⁰⁰ pass through the partitions 18, and are lo-

cated above the bottom filler strips 21. The purpose of the rods 24 and 25 will be presently pointed out.

In each compartment of the cabinet, at 5 the bottom thereof, is mounted a support and ejector member for the record disk. This member is a lever 26 fulcrumed intermediate its ends on the rod 24 extending horizontally between the end walls 10 of 10 the cabinet. The forward end of the lever is provided with an extension 27 which projects a short distance from the open front of the cabinet and the compartment. In the front portion of the compartment is a stationary track member 28 for guiding the record onto the lever 26, said member being a wooden or other strip having a top groove 29, and being secured in the compartment by the pair of rods 25 extending 15 horizontally between the end walls of the cabinet. The lever 26 also has a top groove 30 for seating the record disk, and the rear end of the lever carries an upstanding record engaging finger 31. The lever extension 27 20 is located beneath the strip 28, and its forward end projects from the strip a sufficient distance so that it may be pressed down with the finger for the purpose of tilting the lever 26 to eject the record disk. In front of 25 the strip 28 is a cross-strip 32 which extends horizontally between the end walls 10 of the cabinet, and bears numbers or other indicia identifying the various compartments so that any desired record may be 30 readily found, the number of the compartment in which the record sought is filed away being of course obtained from a suitable index. The compartment numbers are on a metal strip 33 set flush in the face of 35 the cross-strip 32, as clearly shown in Fig. 8.

The depth of the cabinet is such that the record can roll or slide rearwardly on the lever 26 a distance sufficiently to locate a preponderance of the weight of the record 40 to the rear of the fulcrum 24, which results in the lever being tilted, its rear end going down, and its forward end and the extension going up until said extension engages the bottom of the strip 28. The lever now has a 45 downward and rearward inclination, and hence the record disk is prevented from accidentally rolling or sliding forwardly out of the compartment.

The lever is unbalanced, its forward end 50 being heavier than its rear end, and hence the lever has a normal tendency to tilt so that its forward end goes down and its rear end up, this being the position of the lever at the end of the ejecting stroke, or when it is not 55 occupied by a record.

The operation of ejecting the record from the compartment will be understood from an inspection of Fig. 2. Upon pressing down 60 against the forward extremity of the lever extension 27, the lever 26 is tilted, its rear

end going up so that the finger 31 now pushing upwardly against the record to the rear of and below its center, together with the change in the position of the lever, causes the record to roll or slide forwardly on the 70 lever until it strikes the strip 28. The record is now protruding from the open front of the compartment a sufficient distance so that it may be easily grasped and removed. The strip 28 and the lever 26 are in alignment, and hence when replacing the record, it is necessary only to place it in the top groove of the strip it will then roll rearwardly on the lever, whereupon the lever 75 tilts back to its record retaining position, its rear end going down and its forward end going up. The cross-rail 19 acts as a stop to limit the rearward movement of the record, and strip 28 serves as a stop to limit the forward movement of the record when 80 the lever 26 is given its ejecting stroke, and when placing the record back into the compartment, the strip 28 serves to guide the same to the lever.

The lever may be a strip of wood and its 85 extension a strip of metal as shown in Fig. 5; or it may be made entirely of sheet metal having its edges turned up to form the top groove to seat the record, with downturned ears intermediate its ends through which 90 the fulcrum rod passes. Fig. 6 illustrates the last-described lever structure.

As the forward end of the lever extension 95 27 remains depressed when the record is removed from the compartment, the empty 100 compartments of the cabinet are clearly indicated. The strip 28 has a rearward inclination to facilitate the passage of the record along the same to the lever 26.

Fig. 2 shows how the cabinet is adapted 105 for records of different diameters, a large record being shown in full lines and a smaller record in broken lines. The position of the smaller record when it has been advanced to protrude from the cabinet is 110 shown in broken and dotted lines. The manner in which the records are supported in the compartments and their ejection from the compartment is the same for all sizes 115 of records.

I claim:

1. In a phonographic disk record cabinet, a record compartment having a record exit, a pivoted record-supporting member in the compartment, said member being tiltable 120 for urging the record in the direction of the exit to protrude therefrom, and a stop in front of said member for limiting the travel of the record in the direction of the exit, the aforesaid record-supporting member being unbalanced and provided with an extension located beneath and projecting forwardly from the stop, said extension engaging the bottom of the stop when the record-supporting member is supporting a record, 125 130

and swinging downwardly and away from the stop when the record-supporting member is empty.

2. In a phonographic disk record cabinet, a record compartment having a record exit, a pivoted record-supporting member in the compartment, said member being tiltable for urging the record in the direction of the

exit to protrude therefrom, and a stop in front of said member for limiting the travel ¹⁰ of the record in the direction of the exit, said stop being in alinement with the record-supporting member and having a top groove for guiding a record to said member.

In testimony whereof I affix my signature.

ALFRED H. HAAG.
